ABSTRACT OF THE DISCLOSURE

The rupturable container of viscous processing liquid of a self-developing photographic film assemblage is formed and filled with an accurately predetermined quantity of the liquid by freezing the liquid to form a solidified body, forming and sealing the walls of the container around the solidified body and then thawing the solid body to return it to a viscous, liquid state. A method of assembling a film unit is described in which a wall of the container comprises a portion of another component of the film unit.

In the copending U.S. patent application of Edwin H. Land et al., Ser. No. 622,286, filed Mar. 10, 1967, abandoned and replaced by Ser. No. 5,799, filed Jan. 26, 1970, and now Pat. No. 3,619,192, issued Nov. 9, 1971, there is shown and described a photographic film unit comprising all of the materials and components needed to produce a photographic print including a rupturable container of a viscous, aqueous processing liquid adapted to be distributed within the film unit following exposure thereof to produce a transfer image. The basic components of the film unit are a first or photosensitive sheet including a layer of a light-sensitive image-recording material such as silver halide, a second sheet adapted to be superposed with the photosensitive sheet, at least during processing, to aid in the distribution of the processing liquid between the sheets in contact with the exposed photosensitive sheet and a rupturable container of the viscous liquid processing agent adapted to unidirectionally release the processing liquid in response to hydraulic pressure generated within the liquid by the application of compressive stress to the container.

In the particular form of the photographic film unit disclosed in the aforementioned application, the second sheet is initially secured in superposition with the photosensitive sheet prior to exposure (made through the second sheet) and remains in superposition with the photosensitive sheet following processing by viscous liquid distributed in a thin layer between the sheets. The processing liquid is provided in a container having walls formed of sheet material impermeable to the liquid and gas and sealed in face-to-face relationship around a cavity filled with the processing liquid. The seal around one side of the cavity is weaker than the remainder of the seal and is adapted to become unsealed and form a passage for discharging the liquid contents of the cavity in response to hydraulic pressure generated within the liquid. The construction of this particular form of film unit is such that it is important to provide a very precise quantity of the processing liquid in a cavity having one dimension approximately equal to the width of the area over which the liquid is to be distributed.

Accordingly, it is an object of the invention to provide a method of forming and filling a rupturable container of the type described with a precise quantity of a viscous, aqueous processing liquid, the quantity being not less, and only very slight more, than that required to provide a layer of uniform predetermined thickness over a predetermined area between the sheets.

2

A number of advantages can be realized in the construction of a film unit wherein the container is an integral portion of another component of the film unit, for example, wherein a wall of the container is also a section of the second sheet. Heretofore container forming and filling systems have been designed to utilize, handle and perform a number of operations on the liquid and gas impervious sheet material of which the walls of the container are formed, but have not been adapted to utilize, handle and perform operations on other components of a completed or partially completed film assemblage. On the other hand, film assembly machines adapted to handle and assemble these other components are not readily adapted to the handling of liquids and the filling of containers.

Other objects of the invention are: to provide a novel and improved method of forming and filling rupturable containers with a viscous, aqueous photographic processing liquid which may be performed by equipment that is not required to handle or contact the viscous liquid; and to provide a method as described in which the viscous liquid is solidified by freezing, thereby providing for more precise control over the quantity of the container contents and the distribution of the liquid within the container as well as enabling film-manufacturing equipment to handle the liquid as if it were a solid.

Other objects of the invention will in part be obvious and will in part appear hereinafter.

The invention accordingly comprises the method involving the several steps and the relation and order of one or more of such steps with respect to each of the others which are exemplified in the following detailed disclosure of a preferred embodiment taken in connection with the accompanying drawings wherein:

FIG. 1 is a perspective view, partially in section, of a photographic film unit incorporating a rupturable container of processing liquid fabricated according to the method of the invention;

FIG. 2 is a somewhat schematic, elevational view illustrating the method of the invention;

FIG. 3 is a perspective view of a solidified body of processing liquid illustrating a typical configuration of the solidified body;

FIG. 4 is a somewhat schematic, elevational view illustrating the method of the invention;

FIG. 5 is a view similar to FIG. 1 illustrating a film unit manufactured according to the method of the invention;

FIG. 6 is an exploded, perspective view of the film unit of FIG. 5; and

FIG. 7 is a somewhat schematic, perspective view showing the method of assembling the film unit of FIGS. 5 and 6.

The rupturable container and/or film unit manufactured according to the method of the invention comprises two opposed walls formed of a multilayer sheet material which is impermeable to the liquid and to gas. The walls are rectangular and are bonded to one another around their margins to define therebetween a shallow, elongated rectangular cavity filled with the viscous processing liquid. The seal along one long side of the cavity is weaker than the seal at the ends and at the opposite side of the cavity and is adapted to become unsealed throughout its length when compressive pressure is applied to the container. This weaker seal is approximately equal in length to the liquid-filled cavity so that the liquid is released and discharged from the container cavity in the form of an elongated mass approximately equal in length to the cavity. This basic type of container is well known in the art, being described in U.S. Pat. No. 2,543,181, issued Feb. 27, 1951 and embodied in photographic film sold by

Polaroid Corporation for use in its self-developing cameras.

The container of processing liquid manufactured according to the method of the invention is especially adapted for incorporation in a film unit of the type shown in FIG. 1 of the drawings in which the thickness of the materials comprising the film unit are shown as exaggerated for purposes of clarity and illustration. This film unit, designated 10, comprises photosensitive or image-recording sheet 12, a second or image-receiving sheet 14 and a rupturable container 16 holding a quantity of processing liquid. Sheets 12 and 14 are preferably rectangular and substantially coextensive with one another and are arranged in superposed face-to-face contact with at least one edge of each sheet aligned with one edge of the other. The two sheets are retained in superposed relation by mask sheet 20 in the form of a rectangular sheet large enough to extend beyond the edges of both the photosensitive and image-receiving sheets, secured in face-to-face relation with the second sheet and having lateral edge portions at the sides and at one end folded around the sides and end of the superposed sheets and secured to the margins of the photosensitive sheet. Mask sheet 20 is in the general form of a frame, having a large rectangular medial opening defining the extent of the image produced in the film unit, surrounded by lateral edge portions 24 and end portions 26 and 28. Image-recording sheet 12 includes lateral marginal portions 30 and end marginal portion 34, and sheet 14 includes lateral marginal portions 32 and an end marginal portion 36, the two sheets being located in face-to-face relation preferably with the edges thereof in alignment. The lateral edge portions 24 and end portion 26 of mask sheet 20 are secured around and to, respectively, lateral marginal portions 30 and 32 of sheets 12 and 14 and end marginal portions 34 and 36 of the sheets, effectively binding the two sheets to one another along three sides thereof. In a preferred form of film units shown adapted to produce a reflection print surrounded by a white border and viewed through the second sheet against a white background, at least mask sheet 20 is formed of an opaque white material and container 16 may also include a white outer coating to provide a more aesthetically pleasing product.

Container 16 is of the type shown in U.S. Pat. No. 2,543,181 and is formed by filling a rectangular blank of a fluid and gas impervious sheet material, medially and sealing the marginal sections of the blank to one another to form a cavity 18 for containing processing liquid. The seal between longitudinal marginal sections 38 of the container is weaker than the end seals so that upon the application of a compressive force to the walls of the container in the region of the liquid-filled cavity and preferably, progressively from the opposite side of the cavity, there will be generated within the liquid hydraulic pressure sufficient to separate longitudinal marginal sections 38 throughout the major portion of their length to form a discharge mouth at least equal in length to the length of the cavity. Container 16 is attached to the sheets of the film unit at the edges thereof opposite end portions 34 and 36 preferably with a longitudinal edge of the container butted against the edges of the sheets and with the discharge passage of the container aligned with the facing surfaces of the sheets. Sheets 12 and 14 include, respectively, end marginal portions 40 and 42 and the means for coupling the container to the sheets include end portion 28 of mask sheet 20 secured to end marginal portion 42 of sheet 14 and longitudinal marginal sections 38 of the container so as to bridge the gap between the container and sheet 14; and a relatively narrow strip of tape 44 secured to end marginal portion 40 of sheet 12 and the other longitudinal marginal section 38 of the container to bridge the gap between the container and sheet 12. The mask sheet 20 and strip 44 cooperate to provide a liquid-tight wall between the marginal sections of the container defining the discharge mouth thereof and sheets 12 and 14

and form a conduit for conducting the liquid from the container between the sheets at end marginal portions 40 and 42.

The film unit shown is characterized by an integral unitary structure constructed so that its integrity may be maintained during and after exposure and processing to produce an attractive photographic print protected against injury or damage and having a uniform white border surrounding a well-defined rectangular image that extends to the border. This is accomplished by forming the second or image-receiving sheet of a transparent material and exposing the photosensitive sheet and viewing the final image through the second sheet which functions to protect both the image-recording medium and the final image. The transparent image-receiving sheet and the image-recording sheet may both be formed of conventional film base materials such as cellulose triacetate and are coated on their inner surfaces with appropriate layers. The film unit may be especially designed to produce a full color image and the image-recording sheet will include at least a layer on its inner surface a layer comprising a conventional image-recording medium such as silver halide adapted to be exposed to produce an image.

Film unit 10 is of the type adapted to be processed, following exposure, by moving the film unit with container 16 foremost relative to and between a pair of juxtaposed pressure-applying members, first to compress the container and eject the liquid contents of the container between the photosensitive and second sheets 12 and 14 and then spread the processing liquid in a uniform thin layer between the sheets over an area at least coextensive with opening 22 in mask sheet 20. During movement of the film unit between a pair of pressure-applying members such as rollers, compressive pressure is initially applied to container 16 generating hydraulic pressure in the liquid within cavity 18 effecting the rupture of the bond between longitudinal marginal portions 38 of the container and the discharge of the liquid in the form of an elongated mass between sheets 12 and 14 and end marginal portions 40 and 42. Continued movement of the film unit relative to and between the pressure-applying members causes advancement of the mass of liquid between the sheets toward the opposite end thereof as a thin layer of predetermined thickness between and in contact with the facing surfaces of the sheets. The film unit includes means for controlling the thickness of the layer of processing liquid distributed between the sheets specifically by appropriately spacing apart the pressure-applying members. The spacing between the pressure-applying member and hence, the thickness of the layer of processing liquid is determined by the thickness of the film unit at the lateral margins thereof which in turn is a function of the thickness of photosensitive and second sheets 12 and 14 and the thickness of lateral edge portions 24 of mask sheet 20. Since sheets 12 and 14 are of a substantially uniform thickness throughout, the thickness of the layer of processing liquid is determined by the thickness of mask sheet 20 and is approximately twice the thickness of the mask sheet.

Spreading of the processing liquid to the edges of the area defined by opening 22 in the mask sheet and formation of a transfer image extending to the edges of this area is insured by embossing sheet 14 at its margins to displace lateral marginal portions 32 and end marginal portions 36 and 42 out of the plane of the medial portion of the sheet towards sheet 12 by a distance or depth approximately the thickness of mask sheet 20.

One means for insuring that there is sufficient processing liquid to form a layer of predetermined thickness over the entire area encompassed by mask sheet 20 is to provide in the container a quantity of processing liquid in excess of the minimum quantity required to provide the desired liquid layer. However, it will be apparent from

the drawings that the film unit construction provides very little space for collecting and retaining excess processing liquid so that the quantity of excess liquid must be minimized and the overall quantity of liquid very accurately controlled. What space there is available for collecting and retaining excess is located at the end of the film unit opposite container 16 within end portion 26 of mask sheet 20 and is provided by making one of the sheets, for example, sheet 14, shorter than the other or forming the end sections of either or both sheets with notches (such as shown in FIG. 6).

The film unit illustrated and described herein may be adapted to be exposed and processed to produce a full color positive print and may include all of the materials and reagents required to produce such a print according to the process described in U.S. Pat. No. 2,983,606, issued May 9, 1961, in the name of Howard G. Rogers. A print of this type may take the form of a multicolor dye-transfer image in a dyeable polymeric layer supported on second sheet 14 between the latter and an opaque layer located behind the image between it and the photosensitive medium. This opaque layer comprises the processing liquid, initially provided in cavity 18 of container 16 in sufficient quantity to form an opaque layer of predetermined thickness, e.g., of the order of .004 inch. The processing liquid preferably comprises an aqueous alkaline solution having a high pH at which dye developers in the image-recording medium are soluble and diffusible, and contains an opacifying agent in a quantity sufficient to mask the dye developer retained in the image-recording layer subsequent to processing and a film-forming viscosity increasing agent or agents to facilitate rupture of the container and distribution of the liquid processing agent. The opacifying agent normally will be present in a layer of liquid spread between the transparent image-receiving sheet and the image-recording sheet (which is preferably opaque) in a concentration sufficient to substantially limit, if not prevent, further exposure of the image-recording medium by actinic light transmitted by the transparent image-receiving sheet as well as to form a suitable background for viewing the dye-transfer image formed in the dyeable polymeric layer. Opacifying agents particularly desirable for incorporation in the liquid processing composition are those providing a white background for viewing the transfer image and particularly those compositions conventionally employed to provide a background for photographic reflection prints and for having optical properties particularly suited for the reflection of incident radiation. As previously noted, the liquid should be quite viscous and contain a film-forming material in sufficient quantities to impart a viscosity, for example, in excess of 100 centipoises at a temperature of 20 degrees centigrade and preferably of the order of 100 to 200,000 centipoises at said temperature. A typical liquid processing composition suitable for incorporation in container 16 for use in a film unit of the type described to produce a dye transfer print is as follows:

Water	cc	100
Potassium hydroxide	g	11.2
Hydroxyethyl cellulose (high viscosity) [commercially available from Hercules Powder Co., Wilmington, Del., under the trade name Natrasol 250]	g	3.4
N-benzyl- α -picolinium bromide	g	1.5
Benzotriazole	g	1.0
Titanium dioxide	g	40.0

A typical container structure for producing a dye transfer image approximately 3" square in a film unit of the type described may be formed by folding a rectangular blank of a suitable multilayer sheet material having dimensions approximately 3.5" x 1.25", lengthwise and bonding or sealing the inner surfaces of the two walls to one an-

other around all four sides while forming a cavity adapted to contain approximately 0.9 gram of the processing liquid, the density of which is of the order of 1.6 grams per cc. The shape and size of the cavity and hence the shape and size of the mass of liquid contained therein are subject to very accurate predetermination and in the typical container described by way of example, the cavity may take the form of a relatively thin, elongated parallelepipedon having tapered or beveled edges. In the particular example given, the dimensions may be approximately 3" x 0.55" x .028". A typical water and gas impermeable sheet material for forming the walls of the container and adapted to be bonded to itself by the application of heat and pressure is a multilayer material comprising a support sheet such as 1.25 mil. white opaque glassine paper, an intermediate layer of lead foil approximately 1 mil. in thickness and an inner layer of a thermoplastic polymer such as polyvinyl chloride approximately 1.5 mil. thick.

Reference is now made to FIGS. 2 through 4 of the drawings wherein there is illustrated a method of forming and filling a rupturable container of the viscous processing liquid. The basic step in this method is cooling or freezing the aqueous processing liquid to form a solidified body of the liquid having the shape and dimensions of the intended liquid-filled cavity. This solidified body may then be handled as a solid rather than as a viscous, adhesive and highly corrosive liquid, thereby greatly simplifying the handling and packaging equipment required to fill containers. FIG. 3 illustrates a typical solidified body 50 of processing liquid produced according to the method of the invention by apparatus such as illustrated in FIG. 2. Solidified body 50 as previously noted is generally rectangular, elongated, relatively thin and has beveled edges, the latter being provided to facilitate forming of the cavity and excluding air therefrom.

Body 50 may be produced in a number of different ways, for example as shown in FIG. 2, by depositing a layer or strip 52 of the processing liquid onto the surface of a drum 54 which is rotated continuously and is cooled as by circulating a refrigerant through the drum, to solidify liquid layer 52 as it is deposited continuously on the drum. Layer 52 is deposited on the drum to substantially the desired thickness by a doctoring nozzle 56 and additional control over the thickness of the layer may be had by providing a doctor blade 58 behind the doctoring nozzle for reducing the thickness of the layer after cooling thereof has commenced. The method of forming solidified bodies 50 is continuous and the processing liquid is deposited or cast on and solidified by drum 54 as a continuous strip 52 which is removed from the drum and passes into a suitable cutting device for cutting the continuous strip into individual sections of the requisite dimensions having beveled or tapered edges. The strip or layer of processing liquid may be deposited and solidified on drum 54 so as to have a width equal to the length of body 50 and the edges of the strip may be beveled as the strip is formed by a variety of means including, for example, doctoring or planing the edges, or depositing the layer of liquid in a channel having inclined edges. The surface of drum 54 is provided with a suitable release coat and a scraper 59 may be provided for insuring removal of any residue of the processing liquid from the drum ahead of doctoring nozzle 56. The physical properties, specifically, hardness and flexibility, of the hardened strip of processing liquid may be selectively controlled by varying the temperature to which the processing liquid is cooled. In the process illustrated, it is desired to retain the strip of solidified liquid in a flexible condition to permit the strip which is cast on a cylindrical drum to be straightened into a planar configuration, the desired configuration of the pod cavity. This is made possible as a result of the composition of the processing liquid, particularly the presence therein of the polymeric film forming agent. It has been found that the liquid will be sufficiently solidified to permit

handling as a flexible or plastic solid at temperatures of the order of -5° to -10° F. and will retain some flexibility down to temperatures of the order of -25° F. In the solidified condition the processing liquid is not only flexible but easily cut by conventional web severing and slitting equipment including shears, slitting knives and the like, and at such temperatures, may not be brittle nor does it have a tendency to crack and shatter. This property of the strip or web of solidified processing liquid enables the manufacture of solidified bodies by casting strips having a width equal to either the length or width dimension of the solidified bodies and severing the strip to the length of the other dimension; or casting a strip having a width which is a multiple of a dimension of the solidified body and then slitting the strip to form a multiplicity of strips which are then cut into sections of appropriate length by conventional techniques.

In the method illustrated, solidified bodies 50 are formed by casting a continuous strip having a width equal to the length of the bodies and then passing the strip through a cutting device comprising, for example, a first roll 60 mounting a plurality of cutting blades 62 around its periphery and a backing roll 64 for supporting strip 52 against the cutting blades. Cutting blades 62 are shaped and mounted on roll 60 in such a way as to cut the strip at an angle so as to bevel the edges. In this regard, it should be noted that opposite edges may be beveled in opposite directions as shown in FIGS. 1 and 3 or may be beveled in the same direction as shown in FIG. 2. Following cutting solidified bodies may be loaded immediately into containers or they may be stored indefinitely in the frozen solidified condition. When the bodies are formed as a flexible curbed strip, they may be cooled still further after having been straightened and cut, prior to loading.

Other systems may be employed for forming the solidified bodies of processing liquid including, for example, extruding the liquid through a die having a cross section which is the same as the cross section of the solidified bodies and cooling the die so that the liquid emerges from the die as a continuous strip which is thereafter cut into sections of the desired length. It should be apparent that the solidified bodies adapted to be loaded into containers may be formed by any of a number of conventional systems in which solids (such as metals) are formed by cooling and solidifying a liquid including, for example, casting and cooling the liquid in molds or the like. The solidified liquid has another property which enables the formation of bodies of precisely controlled dimension and this is the deformability of the solidified liquid which enables a strip or body to be further formed by many methods similar to those employed in metal working such as by rolling or extrusion.

Containers may be formed and filled by advancing a strip or web 66 of a multilayer sheet material of the type described, through a folding die or guide 68 which folds the strip longitudinally into a V-shaped configuration. The strip is then advanced through a heat-sealing station in which the inner surfaces of the strip are heat sealed together adjacent the fold. The apparatus for performing these and the preceding operations of the strip may be designed to operate on a continuously moving strip as shown or to operate on an intermittently moving strip directing periods when the strip is not in motion. Accordingly, the heat-sealing station is shown as a pair of heated rollers 70 for engaging and compressing the folded edge portion of the strip as it is advanced continuously between the rollers. The strip passes from rollers 70 to a filling station illustrated as a chute 72 for guiding a solidified body 50 into the V-shaped trough formed by folded strip 68. From the filling station the strip and body 50 are advanced to a forming station in which strip 66 is pressed against the body to deform or emboss the strip so as to form a cavity containing the body and exclude air from the cavity. This is accomplished by apply-

ing compressive pressure to the two faces of the strip by suitable means such as a pair of rolls 74 formed of a pliable elastic material such as a foam elastomer. Alternatively or as an additional step in the process of forming 5 the cavity which contains the liquid and excluding air from the cavity, the strip and body may be compressed between a pair of rigid dies having the desired configuration. The next step in the process is sealing the two faces of the strip together around the remaining three sides 10 of the cavity, that is, transversely at opposite ends of the cavity and along the longitudinal edges of the strip. This is accomplished by compressing the strip between a pair of heated dies in the form of a pair of heated rolls 76. The sealing of the container at the ends and along one 15 side of the cavity may be accomplished in a single operation or in a sequence of operations in which the heat and/or pressure applied to the strips to form the end seals is greater than the heat and/or pressure applied to the longitudinal edge seal so as to form an edge seal adapted to become unsealed in response to hydraulic pressure generated within the liquid within the cavity. Thus the seals may be formed by employing a die having portions heated to different temperatures or by making the three seals in one step and applying additional heat and 20 pressure to the end seals in one step and applying additional heat and pressure to the end seals in a succeeding step. The container thus formed may be subjected to an additional forming operation, either before or after the liquid has been allowed to thaw, in which the container 25 is compressed between a pair of forming dies, e.g., rollers. The last step in the process involves severing successive 30 containers from the strip or containers. This is accomplished in the apparatus shown by a rotary knife 78 adapted to act against an anvil 80 for severing the strip 35 of containers as it is advanced between the knife and anvil.

It should be noted that variations of this process and apparatus are possible and these include, for example, 40 fixed pairs of dies that reciprocate toward and away from one another into and from engagement with the strip which is advanced intermittently and is held stationary during engagement between the dies. It is also possible to vary the order and sequence of some of the steps in the process; for example, the folded edge seal may be 45 made after introduction of the solid body; the end seals may be formed prior to introduction of the solid body; and/or the container can be formed of two separate strips rather than a single strip; and/or the sides of the container may be oriented in horizontal planes rather than generally vertically during filling and assembly. By providing the processing liquid as a solid body, the container forming and filling process assumes many attributes of a packaging process involving liquids, so that the apparatus 50 may be substantially simplified insofar as it is not required to handle and dispense a viscous and highly corrosive liquid. This latter feature makes it possible to form all or a portion of the container from another component of the film unit, such as for example, the second or image-receiving sheet. Ordinarily, film assembly operations and container forming and filling operations are carried out by different equipment because of the nature 55 of the different problems involved, the latter type of equipment being designed to handle the liquid involved whereas the film assembly equipment is not designed to handle liquids, but is designed to manipulate, form, and assemble solid materials usually in the form of sheets or webs.

FIGS. 5 through 7 illustrate a film unit and a method 60 of fabricating and assembling a film unit in which one wall of the rupturable container of processing liquid is a section of the second or image-receiving sheet. This film unit designated 82 is basically similar in both construction and function to film unit 10 and comprises a rectangular 65 photosensitive sheet 84, a second or image-receiving sheet 70

86, and a mask sheet 88. Second sheet 86 includes a first section which is generally rectangular and includes a rectangular medial embossed region in which the image is formed and a smaller end section contiguous to the first section and adapted to form one wall of a rupturable container. This end section, designated 90, is coated on one surface with at least a layer of thermoplastic material and preferably with a plurality of layers adapted to render the end section impermeable to the processing liquid and to gas. These materials are essentially the same materials which comprise the container previously described. Second sheet 86 may be formed, for example, of 5 mil. cellulose triacetate rendered liquid and gas impermeable by laminating a 1.0 mil. film of lead to the end section, employing a suitable adhesive and coating the lead film with a 1.5 mil. layer of polyvinyl chloride.

The photosensitive sheet 84 is secured to second sheet 86 by mask sheet 88, the edge portions of which are adhered to the outer face of the first section of second sheet 86 around the margins of the embossed area and are folded around the end and lateral edges of the sheets and are adhered to the margins of the photosensitive sheet. The material of the mask sheet may comprise white paper coated on the surface adapted to be heat sealed with a conventional heat sealing material such as plasticized nitrocellulose. Mask sheet 88 may extend the full length of the film unit as shown in FIGS. 5 and 6, or it may be slightly shorter as shown in the first embodiment of the film unit.

The container of film unit 82 comprises a pair of walls sealed together in face-to-face relation around a liquid filled cavity and, in the form shown, one wall is defined by end section 90 of second sheet 86 and the other wall is defined by a rectangular cover sheet 92 formed of a liquid and gas impermeable laminate, such as previously described, sealed to end section 90 with an edge of the cover sheet butted against the edge of photosensitive sheet 84. A narrow strip or tape 94 is secured in overlapping relation to the longitudinal edge portion of cover sheet 92 defining one side of the discharge passage of the container and the adjacent edge portion of photosensitive sheet 84 for conducting the liquid from the container between the photosensitive and second sheets. The cavity of the container is formed by conforming or embossing cover sheet 92, while end section 90 remains in a substantially planar condition, to the shape of the liquid content of the cavity illustrated in FIG. 6 wherein the liquid is shown as a solid body 96 all four sides of which are beveled in the same direction so that the cross sectional configuration of the liquid body is a bilaterally symmetric trapezoid.

The operations involved in the fabrication and assembly of film units 10 including the forming and filling of the containers, are illustrated in FIG. 7. This process is an essentially continuous assembly line process in which the materials are advanced either continuously or intermittently through various stations of apparatus which form and/or assemble the various components of the film units. The continuous assembly operation in which mask sheet 88 functions as a carrier for the other components of a sequence of film units is the subject matter of application Ser. No. 135,539, filed Apr. 20, 1971, and commonly assigned herewith. Second sheet 86 is provided in elongated form as a strip or web having a width equal to the length of the film unit and coated along one edge portion 90 with the laminae which form one liquid and gas impervious wall of the container. Second sheet 86 is embossed and then advanced to a cutting and laminating station in which sheet 86 is laminated to an elongated mask sheet 88 which has been preformed with rectangular apertures and notches in the margins where the elongated sheet is eventually cut into individual sheets. Mask sheet 88 is laminated by heat sealing to the leading portion of each successive second sheet 86 ahead of the position at which the second sheet is severed, and follow-

ing severance of the second sheet, the remaining portion of the second sheet is laminated to the mask sheet which then functions as a carrier to support and advance the succession of second sheets through the remaining operations in the assembly process. The individual second sheets 86 are mounted on the mask sheet in spaced relation so that the portions of the mask sheet intermediate adjacent second sheets constitute the lateral marginal portions of the mask sheet which are subsequently folded around the sides of the film unit and adhered to the lateral margins of the photosensitive sheets.

During the next steps in the process, a solidified body 96 is deposited on the coated edge section of sheet 86, and a cover sheet 92 is immediately applied in covering relation to body 96 and the edge section of sheet 86 and compressed against the solidified body to form a cavity containing the body while excluding air from the cavity. The next two steps in the process may be performed simultaneously at the same station of the apparatus or in 15 succession, with the first of these being applying heat and pressure to the cover sheet and section 90 of sheet 86 around the margins of the cavity to form the sealed container and locating photosensitive sheet 84 in proper position on the embossed area of second sheet 86 with the lateral and one end edge of the photosensitive sheet aligned with the corresponding edges of the second sheet. The operations in which the solidified body is deposited on the second sheet, the cover sheet is applied and compressed, and heat sealed to the second sheet should be 20 performed in relatively rapid succession so that heat sealing of the container is completed before the frozen liquid returns to a liquid state. This melting time is a function of the temperatures of the solidified body, the coated section 90 of the second sheet and the cover sheet, 25 and may be extended by lowering the temperature of any one of the three components that are assembled to form the liquid filled container.

The succeeding operations in the assembly process include applying and heat sealing a tape to the adjacent 30 edges of the container and the image-recording sheet and severing the container cover sheet and the tape overlapping the container and photosensitive sheet; folding the end marginal section of the mask sheet around the edges of the photosensitive and second sheets; and heat sealing the marginal end section of the mask to the photosensitive sheet. Thereafter the mask sheet is cut midway between successive photosensitive sheets so that the remaining operations in the assembly process are carried out on 35 individual, unconnected film units. These latter operations involve folding the lateral marginal portions of the mask around the edges of the photosensitive and second sheets and heat sealing the lateral marginal portions of each mask sheet to the margins of the photosensitive sheet to 40 complete assembly of each film unit.

It will be noted that during the assembly process, the 45 processing liquid is in the form of a solid body rather than a viscous, highly corrosive liquid and is handled in the same manner as the other components of the film units. The assembly process may be carried out continuously or intermittently, the former, in which the sheet materials are in continuous motion throughout the various stations and assembly operations and the latter in which operations are performed while the materials are 50 stationary at least with respect to the apparatus. It will be seen that solidifying the viscous, aqueous processing liquid facilitates the assembly line production of complete self-developing film units, each containing a precisely predetermined quantity of the processing liquid in a rupturable container without the necessity in the assembly apparatus 55 for special liquid handling equipment.

Since certain changes may be made in the above method without departing from the scope of the invention herein involved, it is intended that all matter contained in the above description shall be interpreted as illustrative and 60 not in a limiting sense.

What is claimed is:

1. In a process of manufacturing a photographic product comprising a container including a pair of walls substantially impermeable to fluids and at least one of which is formed of a flexible sheet material, joined to one another to form a cavity filled with a viscous liquid composition and having a sealed passage adapted to become unsealed to effect the unidirectional release of said viscous liquid in response to the application of compressive pressure to said container, the improvement comprising:
  - cooling a viscous, aqueous liquid photographic processing composition adapted to at least activate a photographic developing agent, to form a solidified body having the configuration of the container cavity to be formed and filled with said liquid;
  - compressing said walls against each other and said solidified body to form a cavity by causing at least said one wall to conform to said body and exclude gas from said cavity between said walls;
  - sealing said walls to one another in face-to-face relation along at least three sides of said cavity, the seal between said walls on one side of said cavity being approximately equal in length thereto and being weaker than the other seals to constitute said sealed passage; and
  - thawing said solidified body to return said body substantially to its original liquid state while retaining the configuration of said cavity substantially unchanged.
2. In the process defined in claim 1, beveling the edges of said body away from one side and introducing said body between said walls with said one side located adjacent said one wall.
3. In the process defined in claim 1, depositing said liquid on the surface of a supporting member as a layer of substantially the same thickness as said body, cooling said supporting member to solidify said liquid, removing the solidified liquid from said surface and cutting the solidified liquid to said size and shape.
4. In the process defined in claim 1, extruding said liquid continuously through a die while cooling said liquid to form an elongated strip having a cross-sectional configuration conforming to said cavity and dividing said elongated strip into sections, each constituting one of said bodies.
5. In the process defined in claim 1, embossing said walls substantially to the shape of said cavity prior to the introduction of said solidified liquid body therebetween.
6. In the process defined in claim 3, rotating a cylindrical supporting member continuously while depositing said liquid on said member and cooling the latter to a temperature such that said solidified liquid remains flexible and removing said solidified liquid from said member as a continuous strip.
7. In a process of manufacturing a photographic film unit including a light-sensitive, image-recording medium adapted to be exposed and thereafter processed by a viscous liquid composition supplied in a cavity of a container comprising rectangular sections of sheet material secured in face relation at the margins of said cavity, and means providing a passage for conducting said liquid from said cavity to a liquid receiving space between first and third sheets, one of which serves as a support for said image-recording medium, said process comprising coating a first area on one side at one end of a first sheet with at least a layer of a thermoplastic material, the improvement comprising:
  - cooling a predetermined quantity of a viscous aqueous liquid composition at least adapted to activate a developing agent for said image-recording medium to form a relatively thin, solidified body smaller than said first area and having the shape of the container cavity to be formed and filled with said liquid;

- positioning said solidified body on said layer of thermoplastic material intermediate the edge of said first area;
- arranging a second sheet, including a layer of thermoplastic material and coextensive in size with said first area on said body in covering relation thereto with the edges of said first area and said second sheet in substantial alignment;
- compressing said second sheet against said body and said first sheet to form said cavity conforming to said body while excluding gas from said cavity between said sheets;
- applying heat and pressure to said sheets at the margins of said cavity;
- arranging a third sheet in superposition with said one side of a second area of said first sheet contiguous to said first area thereof and with an edge of said third sheet contiguous to an edge of said second sheet;
- sealing a cover strip to said contiguous edge portions of said second and third sheets to provide said passage; and
- securing said third sheet to said first sheet at the margins of said third sheet along the remaining edge portions of said third sheet.
8. The process defined in claim 7 wherein said image-recording medium includes silver halide, said film unit includes a silver halide developing agent and said liquid includes an aqueous, alkaline solution for activating said silver halide developing agent.
9. A method as defined in claim 7 wherein said liquid includes an aqueous, alkaline solution for activating a silver halide developing agent.
10. In the process defined in claim 7, embossing said second sheet to the shape of one side of said cavity prior to arrangement thereof in covering relation to said body.
11. In the process defined in claim 8, beveling the edges of said solidified liquid body away from the side of said body in contact with said second sheet.
12. In a method of manufacturing a rupturable sealed container having a cavity of predetermined shape and volume filled with a viscous, aqueous, photographic, processing liquid adapted to at least activate a photographic developing agent, said container including a pair of sections of sheet material bonded together at the margins of said cavity to form a seal completely surrounding said cavity, said sections at one side of said cavity being bonded to form a seal approximately equal in length to said cavity and weaker than the remainder of said seal surrounding said cavity, the improvement comprising:
  - cooling said liquid to form a relatively thin, solidified body having the shape of the container cavity to be formed;
  - introducing said body of solidified liquid between said sections;
  - compressing said sections against opposite sides of said body to form a cavity conforming to and containing said body and to exclude gas from said cavity; and
  - thawing said solidified body to return the latter substantially to its original liquid state while maintaining the shape of said liquid-filled cavity substantially unchanged.
13. In a method defined in claim 12 wherein said liquid includes a water soluble, polymeric film-forming agent initially cooling said liquid until said solidified liquid forms a flexible body and thereafter altering the shape of said flexible body to conform to said cavity.
14. In a method of forming and filling a cavity of a rupturable container with an accurately predetermined quantity of a viscous, aqueous, alkaline, photographic, processing liquid containing a polymeric thickening agent, said container including a pair of walls impermeable to fluids and at least one of which is formed of a flexible sheet material, said method including the steps of sealing said walls to one another at the margins of said cavity, the seal at one side of said cavity being approximately

13

equal in length to said cavity and weaker than the remainder of said seal surrounding said cavity, the improvement comprising:

solidifying said processing liquid by cooling to form a relatively thin body conforming to said cavity;
introducing said body of solidified liquid between said container walls;
compressing said walls against each other and said solidified body to conform said one wall to said body and exclude gas from said cavity between said walls; and
thawing said body of solidified liquid to return said liquid substantially to its original state.

15. In the method defined in claim 14, depositing said liquid on the surface of a supporting member as a layer of substantially the same thickness as said body, cooling said supporting member to solidify said liquid, removing the solidified liquid from said surface and cutting it to the size and shape of said cavity.

20. In the method defined in claim 14, rotating a cylindrical supporting member continuously while depositing said liquid on said member and cooling the latter to solidify said liquid and removing the solidified liquid from said member as a continuous strip, said solidified liquid being

14

cooled to a temperature such that it is flexible when removed from said support member.

17. In the method defined in claim 14, extruding said liquid continuously through a die while cooling the liquid to form an elongated strip having a cross-sectional configuration corresponding to said cavity and dividing said elongated strip of solidified liquid into sections, each constituting one of said bodies.

18. In the method defined in claim 14, embossing said sections of said sheet material substantially to the shape of said cavity prior to introducing said solidified liquid body between said sections.
